Primary Examiner — Caron D Veynar*Assistant Examiner* — Katrina A Betton(74) *Attorney, Agent, or Firm* — Dennison, Schultz & MacDonald(57) **CLAIM**

The ornamental design for a bolt cap, as shown and described.

DESCRIPTION

FIG. 1 is a perspective view of a bolt cap showing our new design viewed from an upper direction;

FIG. 2 is a perspective view thereof viewed from a lower direction;

FIG. 3 is a front elevation view thereof;

FIG. 4 is a right side elevation view thereof;

FIG. 5 is a top plan view thereof;

FIG. 6 is a bottom plan view thereof;

FIG. 7 is a sectional view thereof taken along line VII-VII in FIG. 3;

FIG. 8 is a sectional view thereof taken along line VIII-VIII in FIG. 4; and,

FIG. 9 is a reference view showing the state of use.

The broken line in FIG. 9 shows a vehicle dashboard and center console and forms no part of the claimed design.
